J. S. BUCKWALTER

FEED REGULATOR FOR GRINDING MILLS

Filed July 1, 1924

Inventor.
Jacob S. Bachwalter
by his Attorneys.—
Hanson & Hanson

UNITED STATES PATENT OFFICE.

JACOB S. BUCKWALTER, OF PHILADELPHIA, PENNSYLVANIA, ASSIGNOR TO THE ENTERPRISE MANUFACTURING COMPANY OF PENNSYLVANIA, OF PHILADELPHIA, PENNSYLVANIA, A CORPORATION OF PENNSYLVANIA.

FEED REGULATOR FOR GRINDING MILLS.

Application filed July 1, 1924. Serial No. 723,533.

- One object of my invention is to improve the construction of the means for regulating the feed of a grinding mill, especially of the type used in grinding coffee, spices, &c.
- 5 A further object of the invention is to provide means for adjusting the parts to take up wear without interfering with the adjusting of "coarse", "fine" or "medium" grinding.
- 10 In the accompanying drawings:
- Fig. 1 is a sectional elevation of a grinding mill illustrating my invention;
- Fig. 2 is a sectional view on the line 2—2, Fig. 1;
- 15 Fig. 3 is a sectional view on the line 3—3, Fig. 1;
- Fig. 4 is a plan view illustrating indicating marks on the sleeve;
- 20 Fig. 5 is a sectional view of the extension of the cap plate, showing a detail of the invention;
- Fig. 6 is a sectional view illustrating a modification of the invention; and
- 25 Fig. 7 is an end view of the modification shown in Fig. 6.
- Referring to the drawings, 1 is the body of a grinding mill having a hopper 2 and an outlet 3 for the ground material. A grinding disk 4 is secured to the body portion, as shown in Fig. 1. A rotating grinding disk 5 is confined between a disk 6 and one end of a feed screw 7 by means of screws 8. This feed screw is loosely mounted on a shaft 9 in driving engagement with the shaft 10 of an electric motor 11. Closing the casting between the two shafts is a sleeve 12, having a head 13. Mounted between the head and the end of the feed screw 7 is a coiled spring 14. There is sufficient play between the end of the sleeve and the feed screw to allow the feed screw to have a certain amount of longitudinal movement. The spring 14 tends to force the feed screw and its grinding disk 5 away from the fixed grinding disk 4.
- Secured to the shaft 9 by a pin 16 is a grooved collar 15. Pivoted on the disk 6 is a latch 15^a, which is held by a spring bolt shown by dotted lines in Fig. 1. When the shaft becomes clogged, the latch is released and allows the shaft to turn freely. This mechanism forms no part in the present invention and is described in a separate ap-
- plication filed by me July 1st, 1924, Serial No. 733,534.
- 55 A cap plate 17 is secured to the body portion in any suitable manner. In this cap plate is a bearing 18 for the shaft 9. The bearing is held in the cap plate by a set screw 19. Within an extension 20 of the cap plate is a cam disk 21, in which is located a ball thrust bearing 18^a. The cam disk is prevented from turning in the extension 20 by a lug 22, which extends into a narrow portion 23 of the slot 23 in the extension 20. At the rear end of the cam disk 21 are three cam surfaces, stepped as shown in Fig. 1, which engage corresponding surfaces in a cam block 24, also mounted in the extension and having a lug 25, which extends into the wide portion of the slot 23.
- 60 By this construction, the cam block 24 is allowed a limited rotary movement to adjust the cam disk 21 longitudinally, which, in turn, causes the adjustment of the grinding disk 5 in respect to the grinding disk 4, which regulates the grinding.
- 65 Fig. 5 is a sectional view of the extension 20 and has an internal cross piece 27, which enters a corresponding slot in the end of the cam block 24. In order to adjust the cam block independently of the sleeve, a screw 28 is mounted in the portion 27 and can be turned to move the block 24 longitudinally, independently of the sleeve 26. In order to 70 lock the screw 28 in the position in which it is adjusted, a screw 29 is located back of it, as illustrated in Fig. 1.
- 75 A sleeve 26 is mounted on the extension 20 and has a series of longitudinal ribs 30, which are spaced apart, as shown clearly in Fig. 2. The sleeve 26 has a series of narrow internal projections 31 at its inner end, which are of a width equal to the width of the space between the ribs 30 of the sleeve so that the sleeve can be slipped over the extension and turned to lock the projections 31 back of the ribs 30, which are discontinued, as shown 80 clearly in Fig. 1.
- In order to connect the sleeve 26 detachably to the extension 20, the extension 20 has a series of longitudinal ribs 30, which are spaced apart, as shown clearly in Fig. 2. The sleeve 26 has a series of narrow internal projections 31 at its inner end, which are of a width equal to the width of the space between the ribs 30 of the sleeve so that the sleeve can be slipped over the extension and turned to lock the projections 31 back of the ribs 30, which are discontinued, as shown 85 clearly in Fig. 1.
- 90 In order to hold the sleeve in the position in which it is adjusted, a ball 32 is located in a recess 33 in the cap 17. A spring 34 is located back of the ball and tends to force it forward so that a portion will project 95 into the path of the sleeve. The spring is
- 100
- 105

held by a plug screw 35, which is threaded to the cap plate 17.

In the sleeve 26 is a series of sockets 36, which are arranged to receive the ball 32 so that, on turning the sleeve, the ball is depressed, and, when released, is forced into another socket, frictionally holding the sleeve in the position to which it is adjusted.

The sleeve is marked "Coarse", "Medium" 10 and "Fine", indicating the character of the grinding. The casing may have an indicating pointer, as shown in Figs. 6 and 7, to indicate the position of the particular marks in respect thereto.

15 The operation of the device is as follows:—If it be desired to adjust the movable grinding disk so that the product will be coarse, the sleeve 26 is turned to the position shown in Fig. 4, with the "coarse" mark in line with the pointer on the casing. This movement causes the cam block 24 to back off, allowing the rotating grinding disk to move away from the fixed grinding disk.

When it is desired to produce a medium or 25 fine product, the sleeve 26 is turned to cause the cam block 24 to force the cam disk 21 forward, which causes a longitudinal movement of the shaft 9, and the grinding disk 5 is adjusted to the proper distance from the 30 fixed disk 4. The cam block 24 can be adjusted independently of the sleeve to take up for any wear of the parts by turning the screw 28.

The mechanism is so designed that the 35 adjustments can be made without dismantling the machine.

When it is desired to move the sleeve 26, the sleeve is turned until the internal projections 31 are in line with the spaces between the ribs 30 on the extension 20, after 40 which the sleeve can be withdrawn, and, if necessary, the cam block, cam disk, and ball bearing can be removed.

In Figs. 6 and 7, a modification is illustrated, in which the cam block 24^a is secured to the sleeve 26^a by two screws 37. A pin 25^a on the sleeve projects into an extended slot in an extension of the cap plate 17^a. The screws 37 extend through slots 38 in 50 the end of the sleeve 26^a. By this construction, the cam block 24^a can be adjusted within the sleeve.

In order to retain the sleeve frictionally in its different positions, a plunger 32^a is 55 mounted in the sleeve. Back of this plunger is a spring 34^a. In the end of the extension of the cap plate are sockets 36^a, into any one of which the plunger is projected. On the surface of the extension sleeve are indicating projections 39, which can be aligned 60 with a single projection, or pointer, 40 on the cap plate 17^a.

I claim:

1. The combination in a grinding mill, 65 of a body portion; a fixed disk secured to

the body portion; a rotating shaft; means for rotating the shaft; a feed screw; a grinding disk carried by the feed screw and driven by the said shaft; a cap plate mounted on the body portion and having an extension open at the end; a cam disk located in the extension of the cap plate; means for preventing said cam disk turning in the extension; a cam block back of the cam disk; means for allowing the cam block to have a limited rotary movement; a sleeve mounted on the extension of the cap plate and enclosing the end thereof and means for connecting the sleeve to the cam block so that on turning the sleeve the cam block will be 80 turned and adjusted in respect to the cam disk.

2. The combination in a grinding mill, of a body portion; a grinding disk secured thereto; a cap plate mounted on the body portion; a driven shaft; a grinding disk located opposite the fixed grinding disk and connected to the shaft so that it will turn therewith; a cam disk bearing against the end of the shaft; a cam block back of the 90 disk, said cam disk being prevented from turning, but being allowed to move longitudinally; a sleeve on the cap plate engaging the cam block so that the block can be adjusted with respect to the cam disk to regulate the feed; and a set screw located in the sleeve and bearing against the end of the cam block so that, on turning the screw, the block will be adjusted independently of the 95 sleeve.

3. The combination in a grinding mill, of a body portion; a cap plate secured thereto; a grinding disk secured to the body portion; a shaft mounted on the body portion and having its bearings in the cap plate; a feed screw and rotating grinding disk driven by the shaft; a sleeve mounted on an extension of the cap plate, said extension having a series of longitudinal spaced ribs, the cap plate having internal projections spaced apart and arranged to pass through the space between the ribs and to pass under the ribs when in position so as to lock the sleeve to the cap plate; yielding means for frictionally holding the cap plate in position; a cam disk located in the cap plate and bearing against the end of the flange; means for preventing the said disk from turning; and a cam block mounted back of the disk and engaged by the sleeve so that it will turn therewith to adjust the cam disk and the shaft.

4. The combination in a grinding mill, of a body portion; a cap plate secured to the body portion; a fixed grinding disk mounted in the body portion; a rotating grinding disk opposite the fixed grinding disk; a shaft for driving the said rotating disk; a cam disk mounted in the cap plate and bearing against the end of the shaft; a lug on the 120

disk adapted to the longitudinal groove in the cap plate; a cam block back of the cam disk, and also having a lug adapted to a wide groove so that it will have a limited rotary movement; a sleeve mounted on the cap plate and engaging the block so that the block will turn with the sleeve, said sleeve having a series of sockets; and a spring-pressed ball mounted in the cap plate and arranged to enter any one of the sockets so as to hold the sleeve frictionally in the cap plate.

JACOB S. BUCKWALTER.
